SAFETY ELECTRIC LAMP

Francis R. Meginniss, Albany, N. Y., assignor to
Inertia Devices, Inc., Albany, N. Y., a corpora-
tion of New York

Application February 5, 1934, Serial No. 709,684

4 Claims. (CL 240—11.3)

The Bureau of Mines requires that the circuit of a lamp which is to be used in combustible gases should be broken in case the lamp bulb is fractured and my invention relates to a lamp which complies with these provisions and which is at the same time readily removable and renewable.

It has heretofore been proposed to eject the lamp from its socket in case of the fracture of the bulb, but to normally retain the lamp in position by a fixed stirrup or bail. Such device, however, in order to remove and renew a bulb has required the removal of the socket from the rear of the reflector which has required the disassembly of a number of parts and the expenditure of a considerable amount of time for such renewal.

One of the objects of my invention is the provision of a hinged bail which normally retains the lamp in position in its socket and which may readily be moved away from the lamp to permit removal and renewal thereof.

Another object of my invention is the provision of an axially disposed switch comprising a fixed contact and a movable contact included in the circuit of a lamp which is ejected from its socket in the manner above described and which more quickly opens the circuit of the lamp than does a switch member comprising two movable contacts which have hitherto been used.

Other novel features of my invention will appear in the specification and will be more particularly pointed out in the claims.

My invention will best be understood by reference to the accompanying drawing in which I have illustrated a preferred embodiment thereof and in which—

Fig. 1 is a longitudinal section through a flash lamp which I have chosen to illustrate one embodiment of my invention;

Fig. 2 is a disassembled view of certain parts of my invention;

Fig. 3 is a sectional view illustrating the parts of Fig. 2 in assembled position;

Fig. 4 is a sectional view through the socket illustrating the lamp secured in position therein by the hinged bail;

Fig. 5 is a side view of the socket taken at right angles to Fig. 4 and on a reduced scale; and

Fig. 6 is a fragmentary view, partially in section, illustrating a modification.

Like reference characters indicate like parts throughout the drawing.

Referring to the drawing, 10 indicates generally a casing for a flash lamp and is here shown as comprising two sections one of which 101 is gen-

erally cylindrical in form and the other 102 of which is flared outwardly at its forward end and is provided with screw threads engaging the threaded forward end of the section 101. The cylindrical section 101 is provided with outwardly extending annular beads or ribs 11, the inner end of the section 102 preferably being turned outwardly as best shown in Fig. 1, a suitable gasket 12 being interposed between the inner end of the section 102 and the bead 11 at the forward end of the casing. It will, of course, be understood that the casing may be formed of a single metallic member flared outwardly at its forward end.

The front end of the casing is closed at its forward end by a transparent member 13, which may be in the form of a lens or plain glass. The lens is retained in position by a threaded rim 14 which engages threads on the forward end of the section 102 and which engages the beveled edge of the lens 13, a suitable gasket 15 being interposed between the lens and the forward end of the section 102 of the casing to form a sealed joint and a sealed insulation at the forward end thereof. The inner end of the casing is preferably closed by a threaded cap 16, a suitable gasket 17 being interposed between the forwardly and outwardly turning end of the cap 16 and the annular rib 11.

A battery in the form of one or more dry cells 18 is located within the casing and is adjustable longitudinally thereof by a focusing ring 19 which may conveniently be threaded in the threaded end of the section 101 of the casing and is preferably provided with finger lugs 20. The battery may be grounded by a spring 21 provided the focusing ring 19 is of non-conducting material.

In the embodiment of my invention illustrated, the terminal 22 of the dry cell is engaged by the casing of an inertia operated switch unit 23 which may be of the same character as that illustrated in my application Ser. No. 655,586 which was filed in the Patent Office on or about February 7, 1933 and the details of which have not been illustrated in the present case. The switch is operated by a mass located within the casing of the switch unit, the switch being successively opened and closed by imparting movement to the flash lamp and the switch unit located therein and abruptly stopping such movement.

The forward end of the switch unit 23 is provided with a forwardly extending sleeve 24 which is illustrated as preferably constituting an integral part thereof, though of course, it could be removably secured thereto. The sleeve is in-

teriorly threaded as indicated generally at 25. A fixed contact terminal 26 forming the terminal of the switch unit 23 is arranged axially of the switch unit end of the lamp and extends upwardly within the sleeve 24. A lamp socket 27 threaded at its inner end as at 28 is received in the sleeve 24 of the switch unit. An incandescent lamp 29 is slidably received within the socket 27 and comprises a bulb 30 and the usual base 31. The base of the lamp is illustrated as threaded only because lamps of this character are usually provided with a threaded base. It will be understood, however, that a plain cylindrical base would serve the purposes of my invention. The inner end of the socket 27 is preferably provided with an inwardly extending flange 32 against which is seated a coil spring 33 which is engaged and compressed by the base of the lamp when the latter is inserted in operative position in the socket as illustrated in Fig. 4. The lamp is retained in position by a bail 34 which is hinged as at 35 to a flange 36 which is preferably provided on the forward end of the socket 27. The bail 34 is preferably bent at an intermediate portion thereof to form a generally cup-shaped section 37 which engages the forward end of the lamp 29 and retains the same in the socket against the action of the spring 33 which is thus biased to eject the lamp from the socket. At the same time the bail is movable out of the path of the axial movement of the bulb.

By providing threads on the socket 27 which engage cooperating threads on the supporting means or sleeve 24, the socket may be adjusted along the axis thereof and by rotating the socket, the position of the ball may be adjusted relatively to the contact 26. The foregoing feature is important inasmuch as the overall length of commercial lamps which are suitable for application's use vary, and in the absence of any adjustment, the ball might engage with sufficient force to cause fracture thereof. On the other hand, it would engage an undersized lamp with insufficient force and would cause a loose fit between the two.

In the embodiment of my invention illustrated, a reflector 38 is seated at its forward end against the gasket 15, the inner end of the reflector being provided with an aperture 39 through which the lamp socket 27 passes. The inner end of the reflector 38 is preferably received in a dished member 40 which is provided with an annular flange 41 which is received in a flange 42 on the forward end of the switch unit 23. A coil spring 43 is seated against the forward end of the switch unit 23 between the flange 42 and the sleeve 24, the forward end of the spring engaging the dished member 40.

In case the bulb 30 of the incandescent lamp is fractured, the base of the lamp is unsupported and is ejected from the socket by the coil spring 33 thereby breaking the circuit between the fixed contact 26 and the usual axial contact formed on the base of the lamp. Inasmuch as one of the contacts is fixed, the circuit is opened the instant that the base moves forwardly, and is opened more quickly than is the case where the opening of the circuit is dependent upon the movement of two contact members such as hitherto used. To renew the lamp it is only necessary to move the hinged ball 34 to one side of the axis as illustrated in dotted lines in Fig. 5, insert a new lamp in position within the socket and return the ball to a position in front of the lamp as illustrated in Figs. 2, 3 and 4.

In Fig. 6, I have illustrated a modified form of socket and bail for the incandescent lamp. The bail 44, which is hinged to the socket 27 in any suitable manner, comprises the portions 441 which extend substantially parallel with the axis of the socket. It will be noted that in the embodiment here illustrated the opening 45 in the reflector 46 is of sufficient diameter to permit the socket and the bail of the form above described to pass therethrough. For convenience, the member 46 may be detachably secured to the reflector 46 to form a unit or, obviously, it may constitute a separate element to be fastened to the case as hereinbefore described. Furthermore, the switch unit 23 preferably has a diameter of the order of that of the dry cells 18 in order to facilitate the assemblage of the various elements constituting my flash light. An advantage of this form of socket and bail resides in the fact that the lamp and socket may be removed from either end of the reflector.

While I have described the unit 23 as a switch unit having a terminal at 26, it will, of course, be understood that it may be replaced by a dry cell similar to the cell 18 the terminal of which will replace the terminal 26 and the casing of which will be provided with a socket or sleeve 24 and flange 42 similar to those for the switch unit.

It will also be noted that the socket for the lamp may be fabricated as an integral part of the switch unit to form a structure substantially equivalent to the assembled structure illustrated in Fig. 6 and described above.

While I have described my invention in its preferred embodiment, it is to be understood that the words which I have used are words of description rather than of limitation. Hence, changes within the purview of the appended claims may be made without departing from the true scope and spirit of my invention in its broader aspects.

What I claim is:

1. A portable electric light comprising a switch unit provided at one end with a forwardly extending sleeve, a socket engageable with said sleeve and formed with a support for a yielding means, an incandescent lamp provided with a contact member and the base of which is receivable and slidable within said socket, yielding means interposed between said support and the base of said lamp, a fixed contact with which the contact member of said lamp engages, and hinged means engageable with the bulb of said lamp for normally retaining said lamp in operative position within said socket.

2. A portable electric light comprising a switch unit one end of which is provided with a forwardly extending sleeve and with a fixed contact member extending forwardly within said sleeve, a socket engageable with said sleeve and formed with a support for a yielding means, an incandescent lamp the base of which is receivable and slidable within said socket, yielding means interposed between said support and the base of said lamp, the base of said lamp being provided with a contact engageable with said fixed contact, and hinged means engageable with the bulb of said lamp for normally retaining said lamp in operative position within said socket.

3. A portable electric light comprising a switch unit provided with a casing one end of which is provided with a forwardly extending sleeve and with a contact member extending forwardly within said sleeve, a socket engageable with said sleeve and formed with a support for a yielding means,

- an incandescent lamp the base of which is receivable and slidable within said socket, yielding means interposed between said support and the base of said lamp, the base of said lamp being provided with a contact engageable with said fixed contact, and a ball hinged to said socket and engageable with the bulb of said lamp for normally retaining said lamp in operative position within said socket.
- 5 4. A portable electric light comprising a switch unit of the inertia operated type and one end of which is provided with a forwardly extending sleeve and with a fixed contact member extend-
- ing forwardly within said sleeve, a socket engageable with said sleeve and formed with a support for a yielding means, an incandescent lamp the base of which is receivable and slidable within said socket, yielding means interposed between 5 said support and the base of said lamp, the base of said lamp being provided with a contact engageable with said fixed contact, and hinged means engageable with the bulb of said lamp for normally retaining said lamp in operative position 10 within said socket.

FRANCIS R. MEGINNIS.
